UNITED STATES PATENT OFFICE.

WILLIAM GEORGE JOPSON, OF ABINGTON, MASSACHUSETTS, ASSIGNOR TO ANGLO-AMERICAN TEXTILE MACHINERY COMPANY, OF BOSTON, MASSACHUSETTS, A CORPORATION OF MASSACHUSETTS.

PNEUMATIC SEPARATOR.

1,811,973.

Specification of Letters Patent.

Patented Aug. 5, 1919.

Application filed September 21, 1918. Serial No. 255,029.

To all whom it may concern:

Be it known that I, WILLIAM GEORGE JOPSON, a subject of the King of the United Kingdom of Great Britain and Ireland, 5 residing at Abington, in the county of Plymouth and State of Massachusetts, have invented new and useful Improvements in Pneumatic Separators, of which the following is a specification.

10 This invention relates, generally, to means for separating fibers, and the like, from a current of air in which dust and refuse are present, and has particular reference to a separator for pneumatic card-stripping or 15 card cleaning apparatus for separating from the dust or refuse, the cotton or other salable waste material which adheres to the card clothing or which is embedded therein or lying thereon, and which is drawn there- 20 from, by pneumatic means through a pipe or the like.

In stripping devices now in general use the cotton, or other salable waste material, is separated from the dust and refuse by 25 drawing the air carrying these products through a canvas cylinder, or the like, so as to filter out the fibers, but this method is open to the objections that it is not economical and efficient, and the cotton, or other sal- 30 able waste, has a tendency to become curled and matted, thus reducing the value of the same.

It is the object of the present invention to provide an improved separator which is 35 simple in construction, efficient in operation and by means of which the cotton is separated without being curled or matted, and this latter feature is of great importance as the cotton waste is of greater value if it is 40 not curled.

The above and other objects of my invention are obtained in the embodiment described in the following specification and illustrated in the accompanying drawings, 45 but it is to be understood that the present embodiment is disclosed by way of illustration only and that the invention is not restricted thereto as it is susceptible of various modifications and changes which would be 50 within the spirit of my conception without departing from the scope of the appended claims.

In the accompanying drawing,

Figure 1 is a side elevational view of my improved separator with a portion thereof broken away for purposes of illustration.

Fig. 2 is a sectional view showing the deflector in elevation.

Fig. 3 is an enlarged side elevational view of the coupling or casting housing a deflector, and

Fig. 4 is an enlarged sectional view taken transversely through the deflector and showing its relation to the sides of the chamber in which it is located.

65 Referring to the drawings, wherein like reference characters indicate similar parts in the several views, 10 designates a pipe leading from the card room, it being understood by those familiar with the art that the 70 end of this pipe has a nozzle or the like, the aperture of which is in close proximity to the cards or carding cylinder. The pipe 10 delivers into a union or coupling 11 from the outlet end of which leads a pipe 12 to a dust 75 filtering device hereinafter described and the coupling has a branch provided with an opening 13 which delivers into the top compartment or chamber 14 of a tank 15. As will be seen from Fig. 1, the tank is divided 80 into the cotton receiving chamber 14 and a dust chamber 16 by means of a horizontal partition 17.

The chamber within the coupling 11 is of greater cross-sectional area than the pipe 85 10 and within this chamber and leading from the inlet end of the coupling 11 into the branch opening 13 is a deflector comprising a curved plate 18, the plate being 90 preferably formed of sheet metal and being of less width than the chamber of the coupling so as to provide spaces 19 through which the air current, together with the dust and light refuse carried thereby, is adapted to pass about the plate or chute 95 18. Preferably, the chute 18 increases in width toward its lower end. The deflector 18 is employed to deflect the cotton or other salable waste into the chamber 14, and to increase the efficiency of the device the concave face of the deflector, that is, that face which is opposed to the incoming current of air, is highly polished. The degree of 100 polish upon the deflecting surface may vary

but I have found that the higher the degree of polish, the less is the coefficient of friction between the cotton and this surface and therefore the greater the efficiency. 5 The angle between the deflecting surface and the longitudinal center of the pipe 10, and the radius of curvature and the size of the deflector may vary in accordance with the requirements of the particular machine, 10 but I have found the best results are obtained by making the deflector of greater width than the opening through the conduit or pipe 10 and by bending the edges 20 of the deflector at right angles to the polished 15 surface so that the deflector is channel shape in cross-section, as most clearly shown in Fig. 4. To avoid any shoulders that would impede the escaping dust, the posterior end of the chamber within the coupling 20 slopes conically toward the conduit 12, and this conduit is of greater diameter than the pipe 10.

The pipe 12 may lead to any suitable device for removing the dust from the air, 25 but for illustrative purposes, I have shown the pipe 12 leading to the dust chamber 16 within which is mounted a cloth covered cylinder 21 which cylinder may be rotated by a handle 22. Extending into the interior 30 of the cylinder 21 and forming a bearing for one end of the same is a pipe 23 which leads to a suitable suction device (not shown). In engagement with the exterior surface of the filtering cylinder 21 is a brush 35 24 which when the cylinder is rotated, wipes the dust therefrom. The cotton which collects within the chamber 14 and the dust which collects within the chamber 16 may be removed at the doors 25 and 26, respectively. 40

The operation of the device will be readily understood from the foregoing description. When the suction device (not shown) to which pipe 23 leads is set into operation, a current of air is drawn from the card room through the pipe 10 into the coupling 11 where the current strikes the polished surface of the deflector 18 with the result that the cotton and dust entrained 50 in the air current are momentarily retarded, the cotton being deflected so as to fall into the cotton receiving chamber 14, and the dust, which is lighter than the cotton, being drawn around the edges of the deflector 55 and through the pipe 12 to the dust chamber 16. The air passes from the exterior of the filtering cylinder 21 to the interior thereof, leaving the dust deposited on the exterior surface of the cylinder from which 60 it is wiped by the brush 24 when the cylinder is rotated. It will be seen from the drawings that the pipe 12 is of larger diameter than the pipe 10 and that the enlarged chamber within which the deflector 65 18 is located is in direct communication

with the cotton receiving chamber 14 of the tank 15, and these points are of advantage as a state of vacuum or rarefaction is maintained in the chamber 14 which assists the falling of the cotton or other salable waste. 70

I have found that my improved apparatus is very efficient in operation as it separates practically all of the cotton or other salable waste from the air current, and during the separating operation there is no tendency for the cotton or waste to become curled or matted. 75

What I claim is:

1. In an apparatus for the purpose described, the combination of a conduit through which a current of air is induced including a separating chamber of enlarged cross section having inlet and outlet openings in opposite end walls and a lateral outlet in a side wall, a receiver communicating with the last said outlet, and a deflecting plate of less width than the chamber arranged therein and extending continuously from the inlet to said lateral outlet. 85 90

2. In an apparatus for the purpose described, the combination of a conduit through which a current of air is induced including a separating chamber of enlarged cross section having inlet and outlet openings in opposite end walls and a lateral outlet in a side wall, and a deflecting plate arranged within said chamber between the inlet and lateral outlet thereof, said plate being of less width than the chamber and wider than the inlet thereto and extending continuously from the end wall of the chamber in which the inlet is formed to the said lateral outlet. 95 100

3. In an apparatus for the purpose described, the combination of a conduit through which a current of air is induced including a separating chamber of enlarged cross section having inlet and outlet openings in opposite end walls and a lateral outlet in a side wall, and a deflecting plate arranged within said chamber between the inlet and lateral outlet thereof, said plate being of less width than the chamber and wider than the inlet thereto and gradually increasing in width toward said outlet into which its widest end extends. 105 110 115

4. In an apparatus for the purpose described, the combination of a conduit through which a current of air is induced including a separating chamber of enlarged cross section having inlet and outlet openings in opposite end walls and a lateral outlet in a side wall, and a deflecting plate, of less width than the chamber and of channel form in cross section, extending continuously from the end of the chamber in which the inlet is formed to said lateral outlet, with its channel toward the inlet. 120 125

5. In an apparatus for the purpose de- 130

scribed, the combination of a conduit through which a current of air is induced including a separating chamber of enlarged cross section having inlet and outlet openings in its end walls and a lateral outlet in a side wall, and a curved deflecting plate, of less width than the chamber, extending between the inlet and lateral outlet thereof and having its concave surface toward the 10 inlet highly polished.

6. In an apparatus for the purpose described, the combination of a conduit through which a current of air is induced including a separating chamber of enlarged 15 cross section having inlet and outlet openings in its end walls and a branch outlet through its bottom, a receiving chamber arranged below and communicating with the branch outlet of the separating chamber, 20 and a deflector within the separating chamber comprising a metal plate extending from the inlet end of the chamber to the branch outlet thereof, and having its side edges bent toward the inlet end of the chamber, 25 the width of said deflector being greater than that of the inlet and less than the chamber in which it is arranged.

7. In a device of the class described, a conduit through which a current of air is induced, a separating chamber in said conduit and having a branch opening, the portion of said conduit leading to said chamber being of less cross section than said chamber and the portion of the conduit leading 35 therefrom, a receiving chamber into

which said branch opening delivers, and a deflector in said separator chamber for deflecting the fibers in the air current into said receiving chamber, said deflector comprising a curved plate of smaller area than 40 the cross section of the separating chamber and having its exposed surface polished and increasing in width toward the branch opening, the edges of said deflector being turned toward the incoming current. 45

8. In a device of the class described, a conduit through which a current of air is induced, a separating chamber in said conduit and having a branch opening, the portion of said conduit leading to said chamber 50 being of less cross section than said chamber and the portion of the conduit leading therefrom, a receiving chamber into which said branch opening delivers, and a deflector in said separator chamber for deflecting the 55 fibers in the air current into said receiving chamber, said deflector comprising a plate having its exposed surface polished and increasing in width toward the branch opening, the side edges of said plate being turned 60 toward the anterior portion of the conduit, said plate being in cross section not less than the branch opening and anterior portion of the conduit but being narrower than the separating chamber and posterior portion 65 of the conduit.

In testimony whereof I have hereunto set my hand.

WILLIAM GEORGE JOPSON.
